UNITED STATES PATENT OFFICE.

EDWARD R. BRODTON, OF WASHINGTON, DISTRICT OF COLUMBIA, ASSIGNOR, BY MESNE ASSIGNMENTS, TO SYPHO-CHEMICAL SPRINKLER CORPORATION, OF NEW YORK, N. Y., A CORPORATION OF NEW YORK.

AUTOMATIC FIRE-EXTINGUISHING APPARATUS.

1,303,765.

Specification of Letters Patent.

Patented May 13, 1919.

Application filed August 12, 1914. Serial No. 856,445.

To all whom it may concern:

Be it known that I, EDWARD R. BRODTON, of Washington, District of Columbia, have invented a certain new and useful Improvement in Automatic Fire-Extinguishing Apparatus, and do hereby declare that the following is a full, clear, and exact description thereof.

This invention relates to fire extinguishing apparatus in which the extinguishing fluid, whether a chemical or water, is automatically discharged upon the fire by the opening of sprinkler heads applied to the pipes when a fire-produced temperature exists. Generally 15 stated the object is to provide an apparatus of high efficiency which will be certain to operate under the conditions intended and will not accidentally operate. The special objects and advantages of my invention will be evident from the specific description of 20 embodiments thereof in the following specification.

In its best form the invention contemplates the use of a fire extinguishing fluid supplied through pipes that run to the various parts of the structure to be protected, a building, or a ship, for example, and such fluid in the pipes is under an initial pressure, and an expelling pressure is supplied 25 by a gas generated in a suitable tank, as by a mixture of sulfuric acid and bicarbonate of soda, this mixture being automatically effected.

In the annexed drawings—

Figure 1 is a view in side elevation, with parts broken away, of one embodiment of my invention;

Fig. 2 is a view partly in side elevation and partly in section of another embodiment 40 of my invention, where to give the apparatus a compact form, a single container or holder is employed for the pressure producing chemicals and the chemical fire extinguisher;

Fig. 3 is a detail view in side elevation with parts broken away of still another form 45 of my invention;

Fig. 4 is a detail view of the bottle neck cutter, or knife for opening the sulfuric acid 50 bottle or container shown in Fig. 3;

Fig. 5 is a detail view in section showing a form of bottle opener in which movement

is imparted to an inverted bottle for cutting the bottle closure;

Fig. 6 is a detail view in section of the 55 bottle closure cutter shown in Fig. 5;

Fig. 7 is a detail view on a larger scale of one of the elastic pressure operated devices;

Fig. 8 is a view in side elevation somewhat diagrammatic, showing an embodiment of 60 my invention wherein a number of small units are connected in common with a larger unit for supplementing the supply of extinguishing fluid in the smaller unit;

Fig. 9 is a detail view in perspective of a 65 lever pivoting bracket that may be used with the apparatus shown in Fig. 2.

In the embodiment of my invention shown in Fig. 1, a cylindrical holder or tank 10 is provided for containing a preferably chemical extinguisher, such as pyrene, or tetrachlorid, which has the important properties of quickly and effectively extinguishing a fire while being harmless to human life and non-injurious to fabrics, objects of metal, 70 etc. From the tank 10, and preferably at the bottom, a pipe 11 runs, that is, extended to the various parts of the building, or structure to be protected, which at suitable intervals is provided with well known thermostatic sprinkler heads 12. A short valved extension 13 of the pipe 11 near the tank 10 is provided for filling the tank and the pipe system 11 with extinguishing fluid and for subjecting the same to the desired initial 75 pressure. From the top of the tank 10 the pipe 14 extends which connects with an air dome 15, air in which is subjected to the pressure produced in the tank 10 and the pipe system 11. Preferably a glass gage 16 is 80 connected with the pipe 14 to show the level of the liquid. The pipe 14 has a branch 17 to which is conveniently applied a pressure gage 18, which branch 17 leads to the upper part of a separate cylindrical holder or tank 85 19 in which the pressure is produced by the mixing of suitable chemicals for the expulsion of the chemical extinguisher from the tank 10 and the pipe system 11 on the opening of a sprinkler head. The chemicals for 90 this purpose may be bicarbonate of soda contained in the tank 19 and sulfuric acid contained in a holder or bottle 20 which is supported by a suspending frame 21 in the

upper part of the tank 19. The bringing together of these chemicals is controlled by devices that are put in motion only upon the reduction of pressure in the system, including the tank 10 and the piping 11, so that when a sprinkler head 12 automatically opens the ensuing reduction of pressure brings about the commingling of the sulfuric acid and the bicarbonate of soda in the tank 19 and the generation of a gas in the tank 19 which on passing through the pipe 17 enters the upper part of the extinguisher tank 10 and forces the remaining chemical extinguisher out of the same and through the piping 11 to the open sprinkler head. A check valve 22 in the pipe 17 prevents communication from the tank 10 to the pressure tank 19 while opening under the superior pressure in the tank 19 to establish communication from the latter to the tank 10.

Leading from the top of the chemical extinguisher tank 10 is a vertical pipe 23 whose upper end is turned downward and is connected with the interior of an accordion or bellows-like device 24 (see Fig. 7) that normally is in a contracted or condensed condition, but under internal pressure expands or elongates axially. Said bellows-like device has substantially a cylindrical form, its side walls being sinusoidal in section by the crimping of the thin elastic sheet metal of which it is made, and being closed at one end by an imperforate wall 25 and at the other end having its rim or edge tightly clamped by a screw head or cap 26, and the end of a frame 27 to which the head or cap 26 is screwed. The cap 26 has a central sleeve 28 which is inclosed by the bellows 24 and which is internally threaded a short distance from the outer end of the cap or head 26 by which a screw connection is made with the downturned end of the pipe 23. The sleeve 28 is perforated at intervals with holes 29 that place its interior in communication with the interior of the bellows so that pressure is transmitted through the pipe 23 into the bellows and obviously there can be no escape of the bellows contents and the effect of this pressure is to elongate the bellows.

Bearing against the closed outer end 25 of the bellows 24 is one end of a rod 30 that is slidably mounted in the frame 27 and which at its other end is connected to a lever 31 which is pivoted to an arm or bracket 32 conveniently supported by the pipe 17 and the other end of the lever 31 is connected to a rod 33 of a similar bellows 34 mounted on the top of the tank 39 and forming a means for transmitting movement of the lever 31 to the interior of the tank 19 without the employment of any hole or opening that would result in a joint that might be troublesome to pack to prevent the escape of gas from the tank 19. Upon the rod 30 is secured a collar 35 which is engaged by one

end of a coiled spring 36 whose other end bears against a collar 37 that is engaged by one end of an adjusting screw 38 which engages thread in the frame 27, and thus spring-pressure from the spring 36 is applied through the rod 30 to the closed end of the bellows 24 for the purpose of closing or collapsing the latter when the pressure within the bellows is less than the force exerted by the spring 36 as is the case when a sprinkler head opens. The end of the rod 30 is not attached or connected with the closed end of the bellows so that the easy removal of the rod 30 and the spring 36, when it is necessarily desirable, may be accomplished merely by working the tension nut 38 until the spring is sufficiently weakened to permit the endwise movement of the rod 30 to clear its end from the guide hole in the frame 27.

The bellows 34 that serves to close the opening in the top of the tank 19 has connected to it within the tank the upper end of an open frame 39 that straddles the bottle 20 and below the mouth of the latter carries a circular cutter 400 which upon the upward movement of the frame 39, in consequence of the taking of pressure off the bellows 24 and the ensuing action of the spring 36 is made to cut the seal or closure of the bottle and thus liberates its contents which flow into the tank 19 and mingle with the soda solution.

Still referring to Fig. 1, it will be seen that the bottom of the tank 19 has a pipe 41 which extends to and connects with the pipe 11 and in the pipe 41 is a check valve 42 that prevents pressure from the pipe 11 forcing fluid through the pipe 41, but allows the fluid contents of the tank 19, when there is no greater pressure from the tank 10, to flow into the pipe 11 so that when the apparatus is in operation both the fluid from the chemical extinguisher container 10 and the contents of the tank 19 may be discharged from the open sprinkler head. This action is utilized by providing in the tank 19 with the soda solution, sal ammoniac, or some other fireproofing agent, which, being applied to objects previously ignited but when the fire has been extinguished, will fire proof the same, that is to say the surface will be coated with an incombustible material which will eliminate the danger of subsequent ignition of such objects. The mere wetting down of such surfaces is an important advantage in preventing the immediate recurrence of the fire. A cock 411 is provided to adjust the flow through the pipe 41 or to cut it off entirely, if desired.

As shown in Fig. 1, I provide an alarm in the form of a bell 43 which is operated by a bellows device 44 similar to that shown in Fig. 7, which is in communication with the interior of the pipe 11; and a hand con-

trolled valve 45 is provided in the pipe 11 so as to cut off the flow of fluid through the pipe 11 when enough has been discharged through the automatically opened sprinkler head.

In the form of my invention illustrated in Fig. 2, a very compact apparatus is provided because instead of having the chemical extinguisher tank and the pressure producing tank separated from each other a single tank 100 is provided, which at midlength has a wall or partition 101 that provides in the lower part a container for the chemical fire extinguishing liquid and in the upper part a container for the soda solution and the sulfuric acid holding bottle 20. The piping 111 runs from the lower part of the tank 100 having a similar equipment as to sprinkler heads, alarms and shut off valves, as the apparatus shown in Fig. 1; and an air dome 150 is connected with the upper part of the extinguisher container in the tank 100. A pipe 230 passes through the partition 101 in the upper part of the chemical extinguisher container, and emerging through the top of the tank 100 is equipped with a bellows device 240 similar to that illustrated in Fig. 7, and shown in Fig. 1, which by a lever 310 is connected with a bellows 340 applied to the opening in the tank 100 for operating the bottle closure cutter 400, which is similar to that shown in Fig. 1. The pressure generated in the upper compartment of the tank 100 by the mixing of the sulfuric acid and the soda solution is transmitted through a pipe 170 which leads from the upper part of said upper compartment down into the upper part of the lower fire extinguisher liquid compartment, a check valve 220 being provided to prevent communication from the lower compartment to the upper compartment so that only the gas produced in the upper compartment can flow through the pipe 170. The lever 310 may be conveniently pivoted upon a bracket 311 detachably mounted upon the frames of the two bellows devices. A filling nozzle 102 is provided near the upper part of the lower compartment in the tank 100 so that the extinguishing fluid may be thereby placed in the latter.

In Fig. 2 there is shown a pipe 410 corresponding with the pipe 41 in Fig. 1, a check valve 420 corresponding with the check valve 42 in Fig. 1, and a stop cock 411² corresponding with the stop cock 411 in Fig. 1, to enable the discharge from the pressure tank of some fire-proofing agent, just as in the case of the construction shown in Fig. 1.

In the form of my invention illustrated in Fig. 3, there are two separate tanks, as in Fig. 1, and the bellows device 24 instead of being applied to a pipe leading to the tank 10 is applied directly to the side wall of the latter and is connected by a rod 300 directly to the bellows device 34 applied to the side

wall of the tank 19 and to which on the interior of the tank is connected a rod 390 which (see Fig. 4) has a knife edge 480 carried by a loop 401 on the rod 39 that straddles the metal closure of the bottle 20 so that upon the sliding of the rod 300 consequent upon the reduction of pressure in the tank 10 the closure of the bottle will be sheared or cut and the sulfuric acid contents of the bottle liberated.

In the form of my invention shown in Fig. 5, instead of moving the cutter 491 it is mounted on a fixed frame 391 and the bottle 20 is made vertically movable, movement being imparted to it by the rod 392 connected with the bellows device 34 and thereby the bottle closure forced over the cutter 40 and cut open. In Fig. 6 the cutter has a threaded shank 481, by which it is adjustably attached to the supporting frame 391 so that it may be moved to a position not to interfere with the removal of the bottle or its replacing in the frame 391, which supports it. As clearly shown in Fig. 6, the cutter 40 is made separate from the shank 481 and upon its tapering exterior there are downwardly projecting barb-like ribs 405 and the cutting edge is interrupted for about one-third of the circumference by a notch or depression 406. With this construction when the cutter 40 is forced through the bottle closure only a portion of the latter will be severed, no cut being made opposite the notch 406, but the severed portion, will, by the upward movement of the cutter be forced up into the bottle, remaining attached by the uncut portion and the barbs 405 will interlock with the edges of the cut and the cutter 40 will thereby be retained in the bottle when the shank 401 is afterward withdrawn. Thus, I make it certain that there will be no obstruction to the efflux of the contents of the bottle and provide through the cutter 40 a clear passage for the liquid contents of the bottle. If desired, in addition to the central hole 402, the cutter may be provided with the inclined holes 403 which will enable the sulfuric acid to pass into the opening 402 from the side. It will be seen that by reason of the notch 406 the cutter does not completely separate the disk which it cuts out of the stopper, but leaves it attached for a short distance, and being so attached, and as a result of the continued thrusting movement of the cutter the partially cut out disk will be bent upon its connection with the bottle and thrust upward and to one side of the cutter so that it will finally be squeezed between the side of the cutter and inside of the bottle neck, thus leaving an absolutely unobstructed passage through the hole 402.

It may be desirable in some installations, especially on shipboard, to have small apparatuses, as far as the extinguishing fluid

and pressure tanks are concerned, affording a supply of chemical extinguisher which ordinarily would be adequate. Occasion might arise, however, for a larger supply of chemical extinguishing fluid. To meet this requirement I have devised the embodiment of my invention illustrated in Fig. 8, which shows a number of separate units A (three) said units being shown comprising the chemical extinguisher and pressure tanks and supply pipes having the sprinkler head equipment, each unit being independent of each other; and a unit B that comprises a chemical extinguisher holding tank 10 of large capacity and a pressure tank 19 of large capacity. From the chemical extinguisher tank 10 a pipe 11 leads, which has a number of branches 110 corresponding with the number of units A, one branch 110 being connected with the supply pipe of one of the units. Each branch 110 has a check valve 11 which prevents back pressure from the supply pipes of one of the units A, because in such unit and supply pipe a pressure normally superior to that in the tank 10 of the unit B is maintained, and it is only after the practical exhaustion of the chemical extinguisher from a unit A that the supplemental or auxiliary supply from the unit B is called into requisition. A check valve α is provided in the supply pipe of each unit A that prevents back pressure into the chemical extinguisher tank of the unit A, but when the pressure in the chemical extinguisher tank in the unit B equals that of the residual pressure in the chemical extinguisher tank of the unit A, then the chemical extinguishers from both tanks will flow to the supply pipe.

40 It will be seen that by the arrangement illustrated in Fig. 8, the auxiliary supply of chemical extinguisher is available to any one of the series of units A which may be called into operation when the fire calling it into operation requires a greater supply of chemical extinguisher than the unit itself can provide.

It will be understood that the generation of pressure-producing gas by the mixing of sulfuric acid and soda solution in the unit B is effectuated automatically in consequence of the reduction of pressure in the chemical extinguisher tank 10 due to the efflux of such extinguisher occasioned by the demands made upon it by one of the units A.

50 It will be seen that even though the operation of any one unit A may result in exhausting all of its supply of extinguishing fluid and all of the supply in the auxiliary unit B, that the remaining units A are still in readiness for action should a fire occur in the vicinity where they are located.

55 The metal bellows device while very compact gives an extent of movement which is required to cause the release of the sulfuric

acid, that pressure operated devices of other forms cannot give except at practically prohibitive size and operative pressure. As an element in fire apparatus, said bellows device is of great value.

70 It will be evident from the various forms which I illustrate my invention as embodied, that such invention is not confined to any specific embodiment, but its form of embodiment may be greatly varied.

75 Having thus described my invention what I claim is—

1. In fire apparatus, the combination of a holder for an extinguishing fluid having a normally closed outlet, means for maintaining such fluid under pressure tending to cause its efflux, a metal bellows whose interior is exposed to such pressure, consisting of a cylindrical shell with crimped side walls, one end of the shell being closed and the other open, means for clamping the edge of the open end of the shell comprising a cap with a sleeve extending within the shell, and which is perforated to communicate with the interior of the shell, and an external device adapted to be actuated by said bellows and connected with the closed end of the shell.

80 2. In fire apparatus, the combination of a holder for an extinguishing fluid having a normally closed outlet, means for maintaining such fluid under pressure tending to cause its efflux, a bellows whose interior is exposed to such pressure, a pressure tank, a second bellows whose interior communicates with the interior of said tank, means for controlling the generation of pressure in said tank connected operatively with said second bellows, and an operative connection between said two bellows.

85 3. In a fire apparatus, the combination of a holder for an extinguishing fluid, a separate fluid holder that also constitutes a pressure tank, a pipe leading from the latter to said first mentioned holder for the transmission of pressure to such first mentioned holder, an outlet pipe leading from said first mentioned holder for the delivery of the extinguishing fluid, and an outlet from said separate fluid holder communicating with said outlet pipe for the delivery to said outlet pipe of fluid from said separate fluid holder by the action of the pressure therein.

90 4. In fire apparatus, the combination of a holder for an extinguishing fluid having a normally closed discharge outlet, a pressure tank, means for generating pressure in said tank by the mixing of chemicals therein, a connection between the tank and the holder for transmitting fluid pressure to said holder, and a connection between said tank and said discharge outlet for delivering fluid thereto from the pressure tank, whereby simultaneously, two kinds of fluid may be discharged from said outlet.

95 5. In fire apparatus, the combination of a

- holder for an extinguishing fluid having a normally closed outlet, means for normally maintaining two chemicals separate from each other, having a closure adapted to be cut, and means for cutting said closure including a cutter having an opening or passage through it, said cutter having an edge that is interrupted by a notch or depression. 5
6. In fire apparatus, the combination of a holder for an extinguishing fluid having a normally closed outlet, means for normally maintaining two chemicals separate from each other, having a closure adapted to be cut, and means for cutting said closure including a cutter having an opening or passage through it, said cutter having an edge that is interrupted by a notch or depression, the cutter having a bottle-engaging projection on its exterior. 10
- 15 7. In fire apparatus, the combination of a holder for an extinguishing fluid having a normally closed outlet, means for normally maintaining two chemicals separate from each other, having a closure adapted to be cut, and means for cutting said closure including a cutter having an opening or passage through it, said cutter having an edge that is interrupted by a notch or depression, the cutter having a bottle-engaging projec- 20
- 25 tion on its exterior, and an actuating device 30 for the cutter with which the cutter is loosely connected, whereby the cutter is retained in the opening it makes upon the withdrawal of said actuating device. 35
8. In fire apparatus, the combination of a holder for an extinguishing fluid having a normally closed outlet, means for normally maintaining two chemicals separate from each other, having a closure adapted to be cut, and means for cutting said closure including a cutter having an opening or passage through it, said cutter having an edge that is interrupted by a notch or depression, the cutter being tapered externally and having bottle-engaging barbs on its exterior, an actuating device for said cutter with which the latter has a loose connection, whereby the cutter is retained in the opening it makes upon the withdrawal of said actuating device. 40 45
- 50 In testimony that I claim the foregoing I have hereunto set my hand.

EDWARD R. BRODTON.
